UNITED STATES PATENT OFFICE

EDWARD L. FARLEY, OF JONESBORO, ARKANSAS

HULL EXTRACTOR AND CLEANER

Application filed June 11, 1929. Serial No. 370,059.

The present invention relates to hull or burr extractors and cleaners, one object of the invention being the provision of apparatus in which there is a master unit to which 5 may be added auxiliary or additional units for operating upon the different types of picked or roughly gathered cotton, that is to say, since cotton is not uniformly gathered due to labor, climatic or other conditions, 10 this invention is elastic in design so that it may be installed as complete, or additional units added as desired.

A further object of the present invention is the provision of apparatus of this type 15 which contains many of the essential elements of my three patents granted April 16, 1929, being numbered 1,709,663, 1,709,714 and 1,709,715 respectively, the present structure, however, being so modified as to provide for 20 increased facilities by making provision for two or more compartments for extracting hulls or burrs from cotton and enlarging the area for cleaning it.

With the foregoing and other objects in 25 view, which will appear as the description proceeds, the invention resides in the combination and arrangement of parts and in the details of construction hereinafter described and claimed, it being understood that changes 30 in the precise embodiment of the invention herein disclosed can be made within the scope of what is claimed without departing from the spirit of the invention.

In the accompanying drawings,

35 Figure 1 is a sectional view of the main apparatus as related to a lint flue, gin flue and gin stand, the latter being shown diagrammatically;

Figure 2 is a similar view of the structure 40 shown in Figure 1 with an additional set of cleaning apparatus for acting upon the cotton;

Figure 3 is a view similar to Figure 1 of an apparatus having additional hull or burr 45 separating mechanism mounted therein with a similar number of cleaning elements as shown in Figure 2.

Referring to the drawings, and more especially to Figure 1 thereof, the lint flue L 50 and gin flue F are disposed in the usual man-

ner, the present mechanism being associated therewith and above the gin stand G.

The main casing 4 which carries the present mechanism is provided with inlet 5, which has disposed therein the two feed rolls 6 directly above the star roller 7, there being provided in cooperative relation with the star roller a grooved plate or valve 8 which is adjustable to or away from the star roller 7 and which is similar in construction to that shown in my issued Patent No. 1,709,715, but in which the star roller 7 is preferably operated in a reverse direction; in fact the structure so far described is similar to that shown in said patent. Disposed within the casing 4 so as to direct the cotton to be treated in one of two directions is a valve 9, which when wide open permits the cotton to enter the passageway or duct 10 and there to be acted upon by cleaning rollers 11, 23 and 22, the cotton being delivered on top of roller 11, to be in turn delivered to rollers 23 and 22, to be returned in reverse order over screens 24, 25 and α and directed through the apron or chute 12 to the roll box of gin (not shown) or other place of deposit, it being understood that the application and operation of the invention is not confined to a gin stand. This portion of the mechanism is employed when the cotton is burdened only with light field trash and hulls in such limited quantity that the usual huller gin will discharge them.

In order to act upon cotton which is excessively hilly, or what is known as snaps or bollies, and thus remove them from the cotton, first having been acted upon by proper adjustment of the valve or plate 8 to the star roller 7, the valve 9 is placed to assume the position shown in Figure 1 so that the material is directed to the left and is acted upon by the hull extracting mechanism which includes the saw cylinder 14, a spiked or fluted stripper 16, the brush 19 and the spiked spiral conveyors 15 and 17, which perform a dual office, in that conveyor 15 delivers the cotton to the saw cylinder 14 transversely of the machine and longitudinally of the saw cylinder from each end to center and conveying hulls and remnant cotton by the lower or bottom side through conveyor box 100

15 to its opening as in my former patent where the remnant cotton and hulls are deposited on spiked spiral conveyor 17, which in like manner acts upon the residue of cotton and hulls from center to each end, so that when the hulls or burrs are finally delivered the loss of cotton is negligible. In this operation, a considerable portion of the shale, leaf and field trash is separated from the cotton, and goes out with the hulls into chamber C where same is passed from the housing 4 by the conveyor 20 or other suitable device. This particular hull separating mechanism is somewhat similar to that shown in my issued patents referred to and is here positioned so that the cotton, after being removed from the saw cylinder 14 by the brush 19, will deliver it into the curved chute 21 and to the cleaning rollers 22, 23 and 11, and from whence shale, leaf or other field trash is removed and delivered through respective screens 24, 25 and α , into the compartment 26 to be removed by the conveyor 27 or other suitable device. The clean cotton is thus carried upwardly by the cleaning rollers 22, 23 and 11 to delivery apron or chute 12.

As before stated, Figure 1 is the main apparatus, but to provide an additional cleaning action to the cotton, the structure as illustrated in Fig. 2 is desirable, the reference letters primed indicating similar elements described for Fig. 1, and in addition thereto a chute or passageway 28', instead of being curved, is inclined and directs the treated cotton to cleaning roller 29' by which it is delivered to the respective rollers 30 and 31 and thence through the chamber 26' to the cleaning rollers 22', 23' and 11' and out of the apron or chute 12'. Disposed in cooperation with cleaning rollers 29, 30 and 31 are screens 32, 33 and 34. The treatment of cotton, when diverted through channel 10', is the same in Fig. 2 as in Fig. 1, except that the cotton is carried on the top of rollers 11', 23', 22', 31' and 30' to roller 29' to be returned and cleaned over the screens 32', 33', 34', 24', 25' and α for delivery to apron or chute 12'. Therefore, it will be further understood that in the operation of cotton through the hull separating division a considerable portion of shale, leaf and field trash is discharged with the hulls or burrs, and that the several cleaning rollers or elements for cotton entering through channel 10', in reality become re-cleaning rollers, thus giving the cotton additional cleaning action.

In order to provide an apparatus for more thoroughly removing hulls or burrs from cotton, the apparatus as illustrated in Figure 3 is employed and the elements therein which correspond to those in Figures 1 and 2 are provided with double prime, so that the only addition to the present structure over that of Figure 2 is an additional hull separating apparatus which consists of saw cylinder 36

cooperating with brush 41, stripper 38, spiked spiral conveyors 37 over box or trough 37' and spiked spiral conveyor 39 over screen box or trough 40, to screen the cotton before hulls or burrs are finally delivered into compartment C. The action of these parts is similar to that in Figures 1 and 2.

What I claim is:

1. A cotton cleaning apparatus comprising a casing having an inlet portion adapted to receive cotton directly from a distributor, feeder and breaker rolls in said inlet portion, a compartment in said casing having inclined upper and lower walls, screen means in the bottom of said compartment, a series of cleaning rolls in said compartment over said screen means arranged at different elevations with their axes in a plane substantially parallel with said walls to insure maximum sifting action, a duct below the inlet portion communicating with the top of the compartment for passage of the cotton to the uppermost cleaning roll, a valve operable to open or close said duct, means below the inlet portion providing a passageway leading to the lower end of the compartment whereby the material will pass to the lowermost cleaning roll when the valve is closed, and hull extracting mechanism in the path of travel of the material from the inlet portion by way of said passageway, and discharge means from the compartment substantially at the top thereof.

2. A cotton cleaning apparatus comprising a casing having an inlet portion adapted to receive cotton directly from a distributor, feeder and breaker rolls in said inlet portion, a compartment in said casing, screen means in the bottom of said compartment, a series of cleaning rolls in said compartment over the screen means arranged at different elevations with their axes in an inclined plane to insure maximum sifting action, a duct below the inlet portion communicating with the top of the compartment for passage of the cotton to the uppermost cleaning roll, a valve operable to open or close said duct, means below the inlet portion providing a passageway leading to the lower end of the compartment whereby the cotton will pass to the lowermost cleaning roll when the valve is closed, and hull extracting mechanism in the path of travel of the cotton from the inlet portion by way of said passageway.

In testimony whereof I have hereunto set my hand.

EDWARD L. FARLEY.
